UNITED STATES PATENT OFFICE.

CARL R. WEYMOUTH, OF NEWPORT, MAINE.

FOLDABLE SEAT.

Application filed February 2, 1928. Serial No. 251,399.

The invention aims to provide a new and improved, foldable, flexible seat for hunters and others, said seat being provided with fastening means for securing its two halves in folded position and with means whereby it may be suspended from the user's belt, in folded condition, when not in use.

A further aim is to provide a seat of the class set forth formed of waterproof material, at least at its lower side. Thus, when it is necessary to place the seat upon any wet or damp surface, incident to use, the moisture cannot permeate through the seat to the user's clothing.

A still further object is to provide a seat embodying sheepskin with its natural wool attached, and a protecting sheet of waterproof material, to which the sheepskin is secured, providing a comfortable waterproof seat.

With the foregoing in view, the invention resides in the novel subject matter herein-after described and claimed, description being accomplished by reference to the accompanying drawing.

Fig. 1 is a side elevation showing one form of the seat in folded position and suspended from a belt.

Fig. 2 is a bottom plan view of the seat shown in Fig. 1, disconnected from the belt and unfolded.

Fig. 3 is a top plan view of the seat shown in Figs. 1 and 2.

Fig. 4 is an edge view of the seat illustrated in the preceding figures.

Fig. 5 is a top plan view showing a seat of somewhat modified form.

The drawing above briefly described, illustrates the preferred construction and while such construction will be herein specifically explained, it is to be understood that within the scope of the invention as claimed, minor variations may be made.

The seat is denoted in a general way by the character S. This seat is formed of flexible sheet material and may be of square or rectangular form as seen in a number of the figures of the drawing, or may be of other shape, such as circular, as seen in Fig. 5.

The seat is foldable along a folding line 6, so that its two halves 7-8, lie against each other, and these halves are provided with snap fasteners 9-10 at edges thereof, remote from the folding line, said fasteners being engageable with each other to hold the seat in folded position.

One of the seat halves is provided with straps 11 embodying loops 12 for engagement with the user's belt 13, permitting suspension of the folded seat from the belt when it is not in use. When use of the seat is desired however, it may be readily unbuckled from the belt 13 and placed in any convenient position.

Preferably, the seat is waterproof, at least at its lower side, so that when it is necessary to lay it upon a damp or wet surface, the moisture cannot permeate through the seat to the user's clothing. In attaining this end, I prefer to employ a flexible sheet 14 of desired size and shape, carrying the straps 11 and the fasteners 9-10, and a sheet 15 of sheepskin stitched or otherwise secured to said sheet 14 and provided with its natural wool 16, which wool is exposed, preferably, although not necessarily. Whether exposed or not, the wool insures that a soft comfortable seat shall be provided.

The device is rather simple and inexpensive, yet is very convenient and desirable for hunters and others finding it necessary to sit upon convenient objects in the open. It may be easily carried by the user's belt, in compact folded condition and when its use is necessary, it may be quickly and easily detached from the belt and placed upon the ground, upon a rock, log, etc. In case of wet weather, the woolen or other seat portion is protected against moisture by the waterproof sheet 14 and hence the user and his clothing are also protected.

Attention is again invited to the fact that within the scope of the invention as claimed, variations may be made. For instance, instead of using the sheepskin and woolen upper portion for the seat, heavy cloth or other desired material could be employed, and instead of the specific snap fasteners

and straps herein disclosed, equivalent fasteners and suspenders may be used.

I claim:

A flexible seat of sheet material water-proof at least at its lower side, one half of said seat being foldable onto the other half when not in use, fasteners at the edges of said seat remote from the folding line of the latter for engagement with each other to hold said

halves in folded position, and suspenders 10 connected to said edge of one of said halves, said suspenders having means for connecting them with the user's belt to suspend the folded seat therefrom.

In testimony whereof I have hereunto affixed my signature.

CARL R. WEYMOUTH.
